UNITED STATES PATENT OFFICE.

WILLIAM M. BAILENTINE, OF LAS CRUCES, NEW MEXICO.

BLUE-PRINT MACHINE.

1,282,668.

Specification of Letters Patent.

Patented Oct. 22, 1918.

Application filed August 10, 1917. Serial No. 185,596.

To all whom it may concern:

Be it known that I, WILLIAM M. BAILENTINE, a citizen of the United States, residing at Las Cruces, in the county of Dona Ana and State of New Mexico, have invented new and useful Improvements in Blue-Print Machines, of which the following is a specification.

This invention relates to photography, and more especially to continuous printing machines; and the object of the same is to produce a device adapted particularly for printing from tracings or the like onto blue print paper or the like, although of course it could be used for other purposes.

The invention consists in details of construction hereinafter more fully described and claimed, and as shown in the drawings wherein:—

20 Figure 1 is a front elevation of this machine complete, and Fig. 2 is a side view thereof, showing it in dotted lines as turned on its gudgeons for a purpose yet to appear.

Fig. 3 is a rear elevation of the machine 25 with the doors of its boxes open and its rods partly withdrawn, and Fig. 4 is a central vertical sectional view with these doors closed.

Fig. 5 is an enlarged detail showing the 30 means for locking and guiding the shade bars.

Fig. 6 is an enlarged detail showing the means for adjusting the collars and flanges on the roller or shaft.

35 Fig. 7 is an enlarged sectional detail, partly in elevation, showing the sensitized paper roll.

The machine is preferably mounted on a 40 wheeled base 1 from which rise two standards 2. The main frame work 3 has trunnions or gudgeons 4 journaled in the upper ends of said standards, and one of them fixedly carries a gear 5 rotating inside its standard, the latter being provided with a 45 pivoted catch 6 to engage the teeth in said gear so that the framework may be set at any desired angle, as indicated by the full and dotted lines in Fig. 2. I have shown and described this form of support as that 50 which I preferably employ, but it is obvious that any other suitable support could be used.

The main framework comprises a pair of

side bars 10 connecting upper and lower boxes 11 and 12, each having a cover or door 13 hinged at one end and latched closed at the other as at 14, so that access to it is possible from what I will call the back of the framework. Between said side bars is fixed a sheet or pane of glass 15, and forward of the glass 60 each side bar carries a strip 16 producing between it and the glass a channel for the extremities of a shade bar 17 which is rectangular in shape and has an outstanding handle 18. To each shade bar is attached 65 a shade 19 which winds around an ordinary spring roller 20 journaled between the side bars 10 next the boxes. By grasping the handle of either shade, the bar 17 may be moved across the face of the glass, and 70 then by means of the handle the shade bar may be turned slightly in the channel behind the strips 16 so as to hold the shade against the tension of the spring in its roller. One shade may be drawn downward part way 75 over the glass and the other upward part-way, and by this detailed structure any part of the sensitized paper can be exposed as the necessities of the case demand.

Behind the glass stands a backboard 25 80 which is of a size to fit closely between the side bars 10 and the two boxes, and the face is covered with a felt mat over which is a soft cloth where it bears against the rear side of the glass 15. This board is 85 strengthened by a pair of upright ribs 24 through which are cut slightly oblique slots 23 registering with strictly upright slots 22 in the side bars 10, and rods 21 are passed through all of said slots for holding the 90 backboard in place. When each rod has been inserted it is pressed downward, and it may move easily downward in the slots 22 whereas in its movement in the oblique slots 23 it presses the backboard toward the glass. 95 To remove the rod, it is raised and then drawn longitudinally out of place as indicated in Fig. 3. I prefer this simple means for locking the backboard in place, although of course other means might be employed if 100 desired. The standards 2 are so spaced that the extremities of the rods pass between them allowing the framework to revolve in its gudgeons so that either the back or the front of the framework can be turned toward the source of light. The contents of

the two boxes are duplicate, and the description for one will suffice for both. The numeral 30 designates a shaft or roller which is slightly oval as best seen in Fig. 6 and provided at its midlength with a transverse slot 31 and in one end with a transverse notch 32. Engaging said notch is the head 33 of a T-shaped shaft 34 journaled in one end of the box and having a crank handle 35 on its exterior. A set screw 36 passes through the other end of the box and a tension spring 36' and into a socket in the opposite end of the roller, and when this set screw is advanced the notch is held on the T-head 33 so that by turning the handle 35 the roller is rotated; whereas, when the set screw is retracted, the roller can be lifted out of place and its notch disengaged from the crank shaft. Loosely mounted on the roller near each end thereof is a collar 37 also slightly oval as seen in Fig. 6, and this collar carries a flange 38. For strips of material of various widths, the collars are turned so that they are loose on the roller, then moved lengthwise thereon to adjust the flanges to the edges of the strips, and then again turned so that they are tight on the roller. For fastening the extremity of a strip of paper or the like to the roller, its corners are cut off oblique and the tongue or reduced tip thus produced is projected through the slot 31 in the roller and the latter turned, thus following the practice adopted in a popular type of camera now on the market. The roller 30 thus described may be used for sensitized paper, and a like roller 39 also mounted in the box may be used for tracing linen or paper. The rollers in Fig. 4 are shown at the upper part of the structure as filled with paper and those at the bottom as empty. The paper is led from the rollers through an appropriate slot 40 in the bottom of the box, behind the shade roller 30, and across the rear face of the glass 15; then through another slot 41 into the opposite box, and wound on the rollers there in a manner which will be clear. It should be remembered that I am describing this machine as used for blue prints, although of course I do not wish to be limited in that respect as it can be used to a still greater advantage for photographic printing.

The use of this machine is as follows: The machine on its wheel base is moved to any desired location, having the framework locked in a perpendicular position, thus occupying less floor space and making the machine easier to handle. After the machine is properly located the catch 6 is disengaged from the gear 5, and the framework is turned into a horizontal position and locked so by the catch 6. The rods 21 are then drawn laterally out of the slotted holes and the operator takes off the back 65 as seen in dotted lines in Fig. 4, and he is

then able to open both roller boxes. The tracing is now rolled on the proper roller, leaving enough to reach across the glass and start on roller in the opposite box. The sensitized or blueprints paper is now started on the proper roller, so as to come on top of the tracing and is connected to the opposite roller in like manner to the tracing. The doors to the boxes are then closed except for the slots 40 and 41. The back is then replaced as before and the rods inserted in their place and moved in the proper direction within the oblique slots to press the mat firmly against the papers over the glass. The catch 6 is then disengaged and the framework turned to a perpendicular position and so locked by catch 6. The machine is now ready to be moved on its wheel base to any desired point for exposing or printing, and the framework is so tilted that the rays of the light used for printing will be at right angles and so left until the printing is completed. The catch 6 is then disengaged from the gear 5 and the framework turned with the back toward the light. The projecting ends of the rods 21 serve as handles by which the said rods may be forced downward, thus causing the back to release the papers under the glass allowing the same to be adjusted by turning the 95 cranks in the rollers in the proper direction to move the paper or tracing to any desired point under the area of the glass. The shade or shades are then adjusted so as to expose the portion of the area of the glass to suit 100 the tracing under the same: after this is done the catch 6 is again disengaged, the framework turned back to a horizontal position, and the operation repeated until the 105 printing is completed. The machine is then moved on its wheel base to any desired place, the framework is set at the same position as for loading, the back is removed, the sensitized paper which has been printed is pulled back through the slot out of the box, and cut off one sheet at a time and washed 110 in the usual way. The framework is then placed in a perpendicular position and left when not in use.

What is claimed as new is:—

1. In a printing frame, the combination with a base having a pair of spaced standards, a framework journaled in said standards, of boxes at the top and bottom of said framework and a glass between them, spring rollers journaled in the framework forward of the glass and adjacent the boxes, shades on said rollers, bars at the free edges of said shades, the framework having channels in which the extremities of said bars are movably mounted and within which they are adapted to be locked when canted, and a back plate behind the glass.

2. In a printing frame, the combination with a main framework having boxes at top 130

and bottom and a glass between them, strips in the side bars of the framework producing channels forward of said glass, a back plate in rear of said glass, and rollers in the 5 boxes; of spring rollers journaled between the side bars of the framework adjacent said boxes, shades wound thereon, and an

angularly shaped bar fixed to the free end of each shade with its extremities traveling in said channels and adapted to be locked 10 therein by canting the bar.

In testimony whereof I affix my signature.

WILLIAM M. BALENTINE.
